UNITED STATES PATENT OFFICE.

SAMUEL R. FEE, OF NEW YORK, N. Y.

CLEANING AND POLISHING COMPOSITION.

No. 886,786.

Specification of Letters Patent.

Patented May 5, 1908.

Application filed October 15, 1907. Serial No. 397,508.

To all whom it may concern:

Be it known that I, SAMUEL R. FEE, a citizen of the United States, and residing at New York, in the county of New York and State of New York, have invented certain new and useful Improvements in Composition of Matter Designed for Use in Cleaning, Scouring, and Polishing Tableware, together with many other metal articles, of which the following is a specification, such as will enable those skilled in the art to which it appertains to make and use the same.

My composition consists of the following ingredients combined in the proportions specified;—furnace coal ashes 1 part, white pipe clay $\frac{1}{2}$ part, glycerin $\frac{1}{4}$ part, water 1 part.

In practice, I first pulverize the ashes and clay and thoroughly mix the pulverized product thus produced. I then thoroughly mix the glycerin and water, and then unite the product thus formed with the product formed by mixing the pulverized ashes and clay. The combined product, thus produced, may be put up in cans in the form of a paste, or it may be pressed into cakes.

The furnace coal ashes herein referred to

are the fine ashes taken from the rear connections of a boiler or boilers.

My improved composition is particularly designed for use in cleaning, polishing and scouring table-ware, but may be used for a similar purpose in connection with various other kinds and classes of metal ware, and also for cleaning floors and woodwork generally.

Having fully described my invention, what I claim as new and desire to secure by Letters Patent, is;

1. The herein described composition of matter consisting of furnace coal ashes, white pipe clay, glycerin and water.
2. The herein described composition of matter consisting of furnace coal ashes one part, white pipe clay one-fifth part, glycerin one-fourth part and water one part, substantially as described.

In testimony that I claim the foregoing as my invention I have signed my name in presence of the subscribing witnesses this 12th day of October 1907.

SAMUEL R. FEE.
